UNITED STATES PATENT OFFICE

HAROLD W. BROWN, OF WILKINSBURG, PENNSYLVANIA, ASSIGNOR TO WESTINGHOUSE ELECTRIC AND MANUFACTURING COMPANY, A CORPORATION OF PENNSYLVANIA.

SWITCH FOR METERS.

1,171,587

Specification of Letters Patent. Patented Feb. 15, 1916.

Application filed June 28, 1911. Serial No. 635,908.

To all whom it may concern:

Be it known that I, HAROLD W. BROWN, a citizen of the United States, and a resident of Wilkinsburg, in the county of Allegheny and State of Pennsylvania, have invented a new and useful Improvement in Switches for Meters, of which the following is a specification.

My invention relates to metering switches, and particularly to switches and connections therefor whereby an ammeter or other suitable instrument may be associated, for measuring purposes, with any phase of any one of a plurality of polyphase or other circuits.

The object of my invention is to provide switches and a system of electrical connections of the character and for the purpose indicated whereby the connections of an ammeter may be changed without interrupting the circuits in which it is adapted to be interposed, and whereby the ammeter may be prevented from becoming associated with more than one phase or circuit at a time.

Figure 1 of the accompanying drawings diagrammatically illustrates a system embodying my invention, and Figs. 2 and 3 similarly illustrate systems embodying modifications of the invention.

In the system of Fig. 1, a single ammeter 1 is employed in connection with a plurality of switches 2, 3, 4 and 5, each of which comprises two adjacent insulated movable conducting segments 6 and 7, the member 6 being provided with a stepped lateral projection 8 that extends into a corresponding recess in the member 7. The segments 6 and 7 are respectively engaged by stationary contact terminals 9 and 10, whereby continuous electrical connections are made thereto.

When the switch occupies its normal position, which is that shown, the narrow end portion of the extension 8 is engaged by a contact terminal 11 and the segment 7 is engaged by two other contact terminals 12 and 13 that are interposed in the path of movement of the intermediate wider portion of the extension and, as the segments are moved, may be engaged, either singly or simultaneously, by the said extension. The shapes of the segments and the arrangement of the terminal members are such that the terminal members 12 and 13 cannot engage the segment 6 simultaneously with the terminal member 11, though they may all simultaneously engage the segment 7.

Corresponding to each of the switches 2, 3, 4 and 5 is a polyphase electrical circuit 14—15—16, here shown either as three-phase three-wire circuits or two-phase three-wire circuits, though some of the circuits 60 may be of one kind and some of the other. In series with each of two conductors 14 and 16 of the said circuits, are the primary windings of series transformers 17 and 18, terminals of the corresponding secondary windings of which are respectively connected to the contact terminals 12 and 13, while the remaining terminals are all connected together and to the terminal members 10 of each of the switches. The terminal member 9 of the switch 2 is connected to one terminal of the ammeter 1, and the terminal member 11 of the switch 5 is connected to the other terminal of the ammeter. The terminal members 9 of the switches 3, 4, and 5 are respectively connected to the terminal members 11 of the switches 2, 3 and 4.

In the normal positions of the switches, which are as shown, the ammeter is not associated with any of the circuits, but is included in a local closed circuit including the segments 6 and the terminal members 9 and 11 of each of the switches, together with the connections between them. If it is desired to measure the currents of the various phases 85 having circuit relations with the switch 2, the said switch should be moved so that first the one and then the other, and, finally, both of the terminal members 12 and 13 engage the lateral extension 8 of the segment 6. For instance, if the terminal member 13 engages the segment extension 8, the meter will be included in a closed circuit with the secondary winding of the transformer 18, which 90 circuit extends from one terminal of the said winding, through terminal member 13, segment 6, terminal member 9, ammeter 1, terminal members 11 and 9 and segments 6 of each of switches 5, 4 and 3, and terminal member 11, segment 7 and terminal member 10 of switch 2.

If it is desired to measure current of the phase having circuit relations with the transformer 17, the switch drum will be moved so that the terminal member 12 alone engages the segment extension 8, whereas, if it is desired to measure current traversing the conductor 15, both of the terminal members 12 and 13 will engage the segment extension 8.

If, when the switch 2 occupies a position other than its normal position, another of the switches 3, 4 or 5 should be moved from its normal or initial position, the ammeter 1 will make measurements with reference only to the circuit associated with the switch 2. In order that this may be clearly understood, assume that the terminal members 12 and 13 of each of the switches 2 and 3 engage the corresponding segment projections 8. A circuit will then be established through the secondaries of the series transformers associated with the switch 2, segment 6 of switch 2, the ammeter 1, segment 6 of switches 5 and 4, segment 7 and terminal member 10 of switch 3 to the common terminal of the secondary windings of the said series transformers. The secondary windings in the circuit associated with the switch 3 are not connected to the ammeter, but will remain short-circuited through terminal members 12 and 13, segment 6 and terminal member 9 of switch 3, and terminal members 11 and 10 and segment 7 of switch 2. The ammeter will, in each case where two of the switches are operated simultaneously, make measurements only with reference to the circuit that is associated with the last switch to the left which does not occupy its initial position. Thus, it is seen that the meter can be associated with but one phase of one circuit at a time, and that, consequently, there is no danger of overloading the meter or of confusing the phases or circuits of which it indicates the currents. Also, that the secondary circuits of the series transformers are not open circuited.

In the system of Fig. 2, the conducting segments of the switches are differently shaped from those of the switches of Fig. 1, the lateral extension 20 of the segment 21 of each switch being simply rectangular in form. The terminal members 22, 23, 24, 25 and 26 correspond respectively in function to the terminal members 9, 10, 11, 12 and 13 of the switches of Fig. 1, the terminal members 24 engaging the lateral segment extensions 20 in the normal or initial positions of the switches, but being prevented, by reason of the arrangement of the parts, from engaging the same simultaneously with the terminal members 25 and 26. The operation of the system of Fig. 2 is similar to that of Fig. 1. The switches of Fig. 2 are similar to those of a co-pending application filed by me of even date herewith, Serial No. 635,907, differing therefrom only in that the terminal members 24, 25 and 26 are somewhat differently spaced or in that the lateral projection 20 is of a different width, the said projection being of such a width that it may not engage the terminal members 25 and 26 simultaneously with the terminal member 24 but such that it may simultaneously engage the terminal members 25 and

26. In its initial position, the said segment projection engages the terminal member 24. Thus, by simple mechanical modifications, a plurality of switches like those set forth in the said co-pending application may be electrically interlocked, thereby avoiding the necessity of providing a single movable handle for a plurality of switches, as described in the said co-pending application, whereby the switches may be mechanically interlocked.

A still further modification of the switch is shown in Fig. 3, in which the lateral projection 28 from one of the segments 29 is of such a width that it may engage but one of the stationary contact members at a time but may engage all of them in succession. In this case, terminals of the secondary windings 30 and 31 of the series transformers are respectively connected to contact members 32 and 33 and their common terminal is connected to another contact member 34, all of said contact members normally engaging the segment 35 and being interposed in the path of movement of the projection 28. Another contact member 36 that is also interposed in the path of movement of the projection 28 and engages the same in the normal or initial position of the switch, is connected in each switch except the last to the right to a contact member 37 of the next switch to the right which continuously engages the segment 29. The contact member 36 of the last switch to the right is connected to one terminal of the meter, and the contact member 37 of the last switch to the left is connected to the other meter terminal. The operation of the system of Fig. 3 is similar to those above described.

I claim as my invention:

1. A switch comprising two conducting segments only having stepped adjacent edges, means for making connections respectively with the said segments, and terminal members that may engage either of said segments and certain of which normally engage one of the segments while another normally engages the other segment but may not engage it simultaneously with the aforesaid members.

2. The combination with an instrument, and a plurality of circuits, of a plurality of switches each of which comprises conducting segments, a terminal member continuously engaging one of said segments, that of one switch being connected to the instrument, another terminal member that may engage either of the segments, that of one switch being connected to the instrument while those of the other switches are severally connected to the aforesaid terminals of the remaining switches, another terminal member that continuously engages the other segment, and still other terminal members

- that may engage either segment, the said members being associated by connection with the said circuits.
3. A switch comprising conducting segments having stepped adjacent edges, means for making connections respectively with the said segments, a terminal member normally engaging the narrowest portion of the stepped extension of one of the segments and interposed in the path of movement thereof, other terminal members interposed in the path of movement of a wider portion of the said stepped extension but normally engaging the other segment.
- 15 4. The combination with an ammeter, and a plurality of polyphase circuits, of a plurality of switches each of which comprises two conducting segments having stepped adjacent edges and terminal members, some 20 of which continuously engage the respective segments and others of which may engage either of them, and connections between the switches whereby the meter may not be simultaneously associated with phases 25 of different circuits.
5. The combination with an instrument, and a plurality of circuits, of a plurality of switches each of which comprises conducting segments and terminal members, some 30 of which continuously engage the respective segments and others of which may engage either of them, and connections between the terminal members normally engaging corresponding segments of different 35 switches.
6. The combination with an instrument, and a plurality of circuits, of a plurality of switches each of which comprises conducting segments and terminal members, some
- of which continuously engage the respective segments and others of which may engage either of them, and connections between non-corresponding terminal members that normally engage corresponding segments of different switches.
7. The combination with an instrument, and a plurality of circuits, of a plurality of switches each of which comprises conducting segments and terminal members, some of which continuously engage the respective segments and others of which may engage either of them, and connections between the switches respectively extending from terminal members that continuously engage segments thereof to terminal members that normally engage the corresponding segments of other switches.
8. The combination with an instrument, and a plurality of circuits, of a plurality of switches each of which comprises conducting segments and terminal members, some of said members being adapted to continuously engage the respective segments and others being adapted to engage either of them, and connections between the switches for respectively extending from terminal members that continuously engage segments thereof to terminal members of other switches that may engage either of the segments thereof.

In testimony whereof, I have hereunto subscribed my name this 21st day of June, 1911.

HAROLD W. BROWN.
